UNITED STATES PATENT OFFICE.

FRED GROSVOLD, OF EAU CLAIRE, WISCONSIN.

CAKE-CUTTER.

SPECIFICATION forming part of Letters Patent No. 668,637, dated February 26, 1901.

Application filed June 12, 1900. Serial No. 20,046. (No model.)

To all whom it may concern:

Be it known that I, FRED GROSVOLD, a citizen of the United States, residing at Eau Claire, in the county of Eau Claire and State 5 of Wisconsin, have invented certain new and useful Improvements in Cake - Cutters, of which the following is a specification.

My invention relates to pastry-cutters; and it has for its object to produce a device of 10 this kind which is convertible from a cake-cutter to a device for cutting other pastry articles, and vice versa.

With this object in view my invention consists in the improved construction and novel 15 arrangement of parts of a pastry-cutter, as will be hereinafter more fully set forth.

In the accompanying drawings, in which the same reference-numerals indicate corresponding parts in each of the views in which they 20 occur, Figure 1 is a perspective view of my improved pastry-cutter. Fig. 2 is a central sectional view of the same shown in one position in full lines and in another position in dotted lines, and Fig. 3 is a horizontal section 25 of same.

Referring more particularly to the drawings, 1 indicates the main cutter of my improved pastry-cutter, which is preferably cylindrical and is provided at its upper end 30 with an opening 2 and a handle 3. A central projection 4 extends down from the opening 2 in the top. A sleeve 5 fits upon the outer portion of the main cutter and has its lower edge provided with corrugations 6. The 35 sleeve may be secured to the cutter in any suitable manner, so as to be movable vertically thereon and be locked in its extended position, with the corrugated portion extending below the lower edge of the cutter. A 40 very desirable means for securing the parts together in this manner consists in providing the cutter with substantially L-shaped depressions 7, within which are fitted inwardly-extending studs or projections 8 upon the 45 sleeve. Instead of the depressions it is evident that the material may be slotted and pins be substituted for the projections upon the sleeve.

Secured to the projection 4 upon the interior of the cutter is a sleeve 9, which is also extensible and may be secured in position by means of L-shaped depressions 10 and studs

or projections 11 in the same manner as the sleeve upon the main portion of the cutter.

In using my improved pastry-cutter when 55 it is desired to cut the pastry into plain circular disks the sleeves are raised to their upper limit, where they will be retained by friction, with their lower edges out of contact with the material to be cut. If it should be desired to provide the disks with circular holes, 60 the sleeve upon the central projection can be drawn down as far as it will come and partially rotated, which will cause the studs thereon to enter the lateral portion of the L-shaped 65 depressions and lock the sleeve against upward movement. The sleeve is made of such length that when it is in this position its lower end will register with the lower edge of the cutter, and will thereby pass through the 70 material being operated upon at the same time that the cutter passes through it; but if it should be desired to provide the disks with crimped or fancy edges of any kind the sleeve upon the exterior of the cutter is drawn down 75 as far as it will come, which will cause the crimped or corrugated edge to project below the edge of the cutter. The sleeve is then given a partial rotation upon the cutter, which 80 will cause the studs or projections thereon to enter the lateral portions of the L-shaped depressions, which will lock the sleeve against upward movement. In this manner the operation of the cutter will provide each disk with an edge corresponding to the outline of the 85 projecting portion of the sleeve. If desired, the sleeve upon the central projection could be made long enough to be extended down so that its lower end would be even with the lower edge of the fancy sleeve when in its extended 90 position. When constructed in this manner, it would be necessary to provide the inner sleeve with two locking-points instead of one.

From the foregoing it will be seen that my improved cutter can be quickly changed from 95 one instrument into another and that it will work equally well in either form and that it can be cheaply manufactured and is not liable to get out of order or become inoperative. I reserve the right to make such changes or 100 alterations from the construction shown in the drawings as will come within the spirit of my invention.

Having thus fully described my invention,

what I claim as new, and desire to secure by Letters Patent, is—

1. In a pastry-cutter, the combination, with a main cutter, the sides of which are provided with substantially L-shaped depressions, of a sleeve thereon, the lower edge of which is corrugated and the upper portion is provided with studs for fitting in said depressions, substantially as described.
2. In a pastry-cutter, the combination, with a cylindrical main cutter, the top of which is provided with a perforation and with a handle, and the wall with L-shaped depressions, of a sleeve upon the wall, the lower end of which is corrugated and the upper portion is provided with studs for fitting in said depression.
3. In a pastry-cutter, the combination, with a substantially cylindrical cutter, the top of which is perforated and provided with a handle, and the wall with L-shaped depressions, of a central projection extending from the perforation in the top of the cutter, provided with L-shaped depressions, a sleeve upon the

main portion of the cutter, the lower edge of which is corrugated and the upper edge is provided with studs for fitting in said depressions and a sleeve upon the projection of such a length that when extended its lower edge will be even with the edge of the main cutter and the upper end is provided with studs to fit within said depressions.

4. In a pastry-cutter, the combination, with a main cutter provided with a central projection, of a sleeve on the cutter and the projection respectively, and means for locking each of said sleeves in its operative position independently of the other one.

5. In a pastry-cutter, the combination, with a main cutter provided with a central projection, of a sleeve on the cutter and the projection respectively, and bayonet-points for locking each of said sleeves in its operative position independently of the other one.

FRED GROSVOLD.
